UNITED STATES PATENT OFFICE.

WALTER L. MARR, OF FLINT, MICHIGAN.

AEROPLANE.

1,053,619.

Specification of Letters Patent. Patented Feb. 18, 1913.

Application filed July 2, 1910. Serial No. 570,134.

To all whom it may concern:

Be it known that I, WALTER L. MARR, a citizen of the United States of America, residing at Flint, in the county of Genesee and 5 State of Michigan, have invented certain new and useful Improvements in Aeroplanes, of which the following is a specification, reference being had therein to the accompanying drawings.

10 In the construction and operation of aeroplanes it is found that one of the chief difficulties of controlling lies in the fact that when the sustaining planes become tilted for any reason transversely to the line of flight, 15 the machine is liable to fall as there is but little resistance afforded by the planes to this movement. Or if there be stability planes, they are so arranged that they offer as much resistance to the movement of the 20 lower part of the machine as they do to the upper part so that while the sidewise movement of the machine due to its tilting may be resisted by these planes, the machine does not tend to right itself.

25 This invention relates to aeroplanes and to an arrangement thereof whereby any tendency in the machine to sidewise movement due to the lateral tilting of the main planes is so resisted that the lower portion 30 of the machine tends to swing under the upper portion as a parachute tends to right itself when falling, and thereby to cause the machine to automatically resume a horizontal position.

35 Another feature of the invention is the provision of auxiliary balance steering planes so disposed that either end of the machine may be raised at will to avoid an obstacle when in flight whereby the aeroplane 40 may be turned in its course, even if the main steering plane or rudder of the machine becomes disabled, the operator still having complete control of the apparatus and directing its flight without the use of the main 45 rudder plane.

The invention consists of the matters hereinafter set forth, and more particularly pointed out in the appended claims.

In the drawings, Figure 1 is a view in elevation of an aeroplane that embodies features of the invention; Fig. 2 is a plan view thereof; Fig. 3 is a view in detail of a balance steering plane.

As shown in the drawings as one preferred form of construction of the bi-plane type, the main frame 1, preferably rhom-

boidal in figure, is formed of suitable materials in proportion to combine the necessary strength with lightness. The frame is supported when on the ground in the usual 60 manner on a wheel truck 2. The main frame is disposed longitudinally to the line of flight of the machine and has suitable lateral extensions 3.

A pair of main planes 4 are supported by 65 the frame and extensions and are preferably secured in sections to the frame work, being inclined to the line of flight of the machine at the proper sustaining angle.

Forward lifting planes 5 preferably disposed in parallel horizontal pairs, are pivotally secured at the forward end of the frame with a tilting bar 6 or other suitable controlling mechanism extending back to the operator's station at the middle of the 75 main body whereby their angle of incidence to the line of flight may be varied as desired.

A rear balance plane 7 is secured at the proper angle to the rear end of the main frame and a main rudder plane 8 that is 80 split to clear the balance plane is pivotally secured to the frame to swing transversely to the line of flight through suitable controlling mechanism of any preferred type extending forward to the operator's station. 85

A balance steering plane 9 is pivotally mounted on each extension of the main frame preferably adjacent to and between the outer sections of the main planes. In preferred form, each consists of a rudder member 10 pivoted at its forward edge to swing on an axis substantially perpendicular to the sustaining or main planes and a balance member split to embrace the rudder plane and pivoted at its forward edge to 95 swing on an axis that intersects the secondary rudder axis at right angles thereto. As herein shown the members swing together on the rudder axis while the balance member is free to be tilted on its own axis independent of the angular position of the rudder member relative to the line of flight of the machine. If the rudder axis is at the forward margin of the main plane, the front edge of the balance plane is slightly curved 100 so that it does not project beyond the main planes when swung with the rudder. The balance plane need not swing in which case proper provision is made to afford movement of the rudder plane. The members 105

are controlled separately through suitable connections running to the operator's sta-

tion where levers, handles or other devices which may be of any preferred type and are herein indicated at 11, are placed in convenient position. The aeroplane is driven by a suitable motor indicated at 12 provided with one or more propellers 13, the motor and operator's station being so disposed that the center of gravity of the machine is well below the upper main plane 10 and preferably is also below the lower main plane. At each end of the lateral extensions of the main frame, stability planes 14 are secured to the upright members of the frame substantially perpendicular to the under 15 face of the upper main plane. One or more of these planes is placed at each end of the machine with its lower margin at a considerable distance above the upper face of the lower main plane and above the center of 20 gravity of the machine. Preferably the stability planes are disposed in pairs on either side of the auxiliary balance steering planes, as indicated herein. By this arrangement of the balance steering planes, 25 the operator may tilt them to augment the lifting power of the main planes or to offset their effect dependent on the angle he gives the balance members. If he wishes to cause either end of the machine to momentarily rise or fall he accomplishes this by depressing or raising the rear edge of the balance member at that end.

The auxiliary planes are preferably pivotally secured to the main frame at approximately the same distance from its center as the main steering plane, and by deflection of the auxiliary rudder members, the machine is made to swing on one end as on a pivot. If any one of the steering 40 planes, either auxiliary or main, become disabled, the operator can control the direction of his flight by proper manipulation of the other two. By simultaneously deflecting the steering planes and depressing the outer balance plane, the outer end of the machine as it wheels, tends to rise, thereby overcoming its inertia which would otherwise rock it the other way.

Another feature is the self-righting character of the machine due to the position of the stability planes. If for any reason the main planes are tilted laterally, the stability planes afford such resistance to the air as to prevent the sidewise movement of the machine which would otherwise occur and as the center of gravity of the machine is well below the upper main plane, and as the stability planes extend only a short distance below the upper plane, the movement of the latter sidewise is retarded while the under plane and the motor swing into place below it with the same motion as that of a loaded parachute. Thus the machine tends to maintain its equilibrium under ordinary conditions and rights itself when swerving

from a direct line of flight. Obviously the stability planes may extend above the upper main plane if so desired.

The pivotal supports of the auxiliary rudders enables the operator to hold the members in line with the path of motion of the machine if desired, so as to afford as little resistance as possible to its forward motion compatible with their lifting or sustaining effect. This reduces the power necessary to drive the aeroplane below that required by aeroplanes of ordinary type.

The planes may be multiplied in number or decreased as the case may be to meet different requirements of service and the position of the several parts may be varied without materially affecting their efficiency.

Obviously, changes in the details of construction may be made without departing from the spirit of the invention and I do not care to limit myself to any particular form or arrangement of parts.

I claim as my invention:

1. In an aeroplane, a main frame disposed longitudinally in the line of flight of the machine, main planes secured transversely on the main frame at a fixed angle to the line of flight, lifting planes angularly adjustable on the forward end of the main frame, a rear balance plane on the back end of the main frame, a main steering plane pivotally secured to the back end of the main frame to swing in a plane transverse to the main plane, balance steering planes adjacent the main planes swinging on an axis perpendicular to the main planes, balance members each angularly adjustable on an axis intersecting a balance steering plane axis, and stability planes perpendicular to the main planes parallel to the line of flight adjacent to the upper main plane.

2. In an aeroplane, a main frame disposed longitudinally in the line of flight of the machine, main planes secured transversely on the main frame at a fixed angle to the line of flight, lifting planes angularly adjustable on the forward end of the main frame, a rear balance plane on the back end of the main frame, a main steering plane pivotally secured to the back end of the main frame to swing in a plane transverse to the main plane, balance steering planes adjacent the main planes, each pivoted to swing on an axis substantially perpendicular to the main planes and provided with a balance member angularly adjustable on an axis intersecting the steering plane axis, and stability planes substantially perpendicular to the main plane secured parallel to the line of flight adjacent to the upper main plane and at an interval from the lower main plane.

3. In an aeroplane, a main frame disposed longitudinally in the line of flight of the machine, lateral extensions therefrom, main

planes secured on the main frame and extensions at a fixed angle to the line of flight, forward lifting planes angularly adjustable on the main frame, a rear balance plane on the back end of the main frame, a main steering plane pivotally secured to the back end of the main frame to swing in a plane transverse to the main plane and divided to embrace the rear balance plane, stability planes substantially perpendicular to the main planes secured parallel to the line of flight adjacent to the upper main plane and at an interval from the lower main plane, balance steering planes each pivotally secured near the extremities of the main plane to swing on an axis at right angles thereto and provided with a balance member tilttable on an axis at right angles to said first axis, and means for manipulating the several steering and balance planes independently.

4. In an aeroplane, a main frame disposed longitudinally in the line of flight of the machine, lateral extensions therefrom, main planes secured on the main frame and extensions at a fixed angle to the line of flight, forward lifting planes angularly adjustable on the main frame, a rear balance plane on

the back end of the main frame, a main steering plane pivotally secured to the back end of the main frame to swing in a plane transverse to the main plane and divided to embrace the rear balance plane, stability planes substantially perpendicular to the main planes secured parallel to the line of flight adjacent to the upper main plane and at an interval from the lower main plane, balance steering planes each pivotally secured near the extremities of the main plane to swing on an axis at right angles thereto and provided with a balance member tilttable on an axis at right angles to said first axis, and means for manipulating the several steering and balance planes independently.

In testimony whereof I affix my signature in presence of two witnesses.
